CRANE HOOK

Raymond F. Van Den Houten, Albany, and Adam R. Akelewicz, Voorheesville, N.Y., assignors to Creative Associates of Albany, Ltd., Latham, N.Y., a corporation of New York

Filed Feb. 21, 1967, Ser. No. 5,908

Term of patent 14 years

(Cl. D41—1)

FIGURE 1 is a perspective view of a crane hook from one side thereof showing our new design;

FIGURE 2 is a side elevation view from the opposite side thereof;

FIGURE 3 is an elevational view from one side thereof; and

FIGURE 4 is an end elevational view from the other side thereof.

The dominant features of our new design are shown by means of full lines in the drawings.

We claim:

The ornamental design for a crane hook, substantially as shown and described.
